(57) **CLAIM**

We claim the ornamental design for an accessory for hairdryers, as shown and described.

DESCRIPTION

FIG. 1 is a top perspective view of an accessory for hairdryers showing our new design;

FIG. 2 is a bottom perspective view thereof;

FIG. 3 is a side view thereof;

FIG. 4 is a front view thereof;

FIG. 5 is a rear view thereof;

FIG. 6 is a top view thereof; and,

FIG. 7 is a bottom view thereof.

The view opposite the side view of FIG. 3 is a mirror image thereof, and therefore, is omitted.

The broken lines in the drawings illustrate portions of the accessory for hairdryers that form no part of the claimed design.
